UNITED STATES PATENT OFFICE.

WILLIAM FREDERICK McMAHON, OF RIVERSIDE, CALIFORNIA.

OIL-WELL PUMP.

Application filed November 2, 1925. Serial No. 66,324.

This invention relates to new and useful improvements in oil pumps as applied to oil wells and means for raising oil from oil deposits in the earth to some height above the 5 surface of the ground.

While the invention is shown applied to pumping oil from oil deposits deep in the earth it may obviously be used for pumping fluids from other forms of fluid containers and used to equally good advantage.

In the illustration I have shown an oil well adapted to be pumped by a U tube pump in which one tube contains the pumped fluid and the other tube contains the forcing liquid, which has a higher specific gravity than the fluid being pumped, and said forcing liquid is moved by a pressure, that is, in this particular case developed by a single acting reciprocating pump. In practice however two or more oil wells each containing a U tube pump may derive their said forcing pressure from a common pressure developing plant.

It is well known that the depth of the oil deposit in an oil well will vary at all times due mainly to the gas pressure in the earth, hence pumping means depending upon the depth of the pump ejection or pump suction pipe in the oil deposit are limited in their 20 operation and volumetric efficiency, and provision is therefore needed for correction.

It is an object of this invention to provide a pumping means that will at all times be independent of a limited depth of its pump ejection pipe or pump suction pipe in the body of oil in the oil well.

Other objects of my improvement are: first, to provide a column of oil and water adapted to be moved in a reciprocating 5 movement in a pumping system in an oil well, to raise the fluid from the oil deposit in the said oil well.

Second: to provide a U tube pumping system in an oil well, utilizing the properties of the fluid being pumped, whereby said fluid will float on water, affording thereby a balanced column of fluid in both tubes, one tube having a column of the fluid being pumped and the other tube having a column of fluid of greater or higher specific gravity whereby the later column of fluid can be actuated

by a pressure at the surface of the earth, to raise the fluid pumped, out of its respective tube.

Third: to provide an oil well pumping system whereby all mechanical moving parts are above the surface of the ground.

Fourth: to afford facilities, whereby several oil wells may be pumped by one pressure developing plant efficiently.

Fifth: to reduce the number of moving parts in an oil well pump. With these and other objects in view the invention resides and consists in the construction and novel combination and arrangement of parts hereinafter more fully described and illustrated and pointed out in the claims hereto appended, it being understood that various changes in the form, proportion, size and minor details of construction within the scope of the claims may be resorted to without departure from the spirit or sacrificing any of the advantages of the invention.

Similar characters of reference denote like or corresponding parts throughout the several figures of the accompanying drawings forming a part of this specification and upon which—

Fig. 1, is a sectional elevation through the U tube and the pressure pumps, showing the general assembled construction.

Fig. 2, is a transverse section through a U tube pump at line "a—a", showing the construction of the fluid passageways.

Fig. 3, is a sectional elevation through the U tube pump on a larger scale, showing the check valve the only mechanical moving part in the pump.

Fig. 4, is a section through delivery passageway, at line "b—b", showing the construction of same.

Fig. 5, is a section through the check valve of the U tube pump at line "c—c", showing the ball valve cage system.

Fig. 6, is a section through the fluid pressure cylinder showing the water tube connection to same.

Referring in detail to the characters of reference marked upon the drawings, 1 represents the oil well which is a hole drilled in the earth from the surface to the oil deposits contained in the earth. After the oil de-

positions are penetrated the pressure in the earth raises a column of oil to a height 2 in the oil well. It is into this column of oil I lower my U tube pumping system which 5 comprises of, as the name implies, two tubular columns 3 and 4, each tube extending from the surface of the earth into the oil well and joining together at some point 5 in the body of oil in the oil well 1. As oil 10 will float on water and the specific gravity of the oil is a slight less than that of water at the same temperature, I provide a column of water in tube 3, and it will balance a column of oil in tube 4, at some point in the lower end portion of the tube 4 near the joint 5, and below the check valve 6. By exerting a pressure on the column of water in tube 3, by means of the plunger 7, of the direct acting pump 8, it can readily be seen 15 that a column of water equivalent to the displacement of the plunger 7, will move an equivalent column of oil in tube 4 through a certain distance, and when the plunger 7, is moved in a reversed direction the said column of oil will do likewise under its own weight, it is upon this reciprocating movement I derive my pumping cycle of operation.

As before stated the column of oil in tube 30 4, and the column of water in tube 3, will balance each other at some point in the actuating cylinder 9 of the tube 4, the plunger 7 of the reciprocating pump 8 in forcing the column of water in tube 3 into the actuating cylinder 9, in turn forces the column of oil floating on the said column of water through the actuating passageway 10 and performs actual mechanical work, as truly as though steam acted on a piston and moved a pump 35 plunger along with it.

A current of any kind be it steam, air, water or other fluid has a tendency to induce a movement, in the same direction, of any body with which it may be in contact. This 40 mechanical principle underlies the action of my improvement in raising the oil from the oil well into the tube 4, through the check valve system 6, and when the plunger 7 has reached its full stroke the check valve 6 closes and the moving column of fluid in the actuating cylinder 9 returns to its former position. The said moving column of fluid when moving upward with an extremely 45 high velocity through the contracted passageway 10, imparts a portion of its velocity to the oil in the delivery cylinder 11, and gives it sufficient kinetic energy to overcome a pressure even higher than the original 50 pressure developed by the plunger 7 on the column of water in the tube 3.

The difference in the velocities of the fluid being forced through the actuating contracted passageway 10, and the delivery contracted passageway 12, together with the slight 55 difference in temperature between the oil in

the oil well and the fluid in the pumping system produces a partial vacuum in the valve body 13.

The velocity imparted to the column of oil in the delivery cylinder 11 gives the latter sufficient energy to throw open the check valve 6 and raise a column of oil from the oil well 1, equivalent to the displacement of the plunger 7 of the pressure developing pump 8.

The pressure developing pump is in this particular case a steam driven, direct single acting reciprocating pump 8, as this pump 8 is of standard construction the principle of which is well known I will only describe the parts pertaining to my invention as all other description would be superfluous. The plunger 7, which is actuated by the steam pressure on the steam piston 20, is outside packed and moves in a reciprocating movement in water cylinder 15 which is, on one end portion attached to the steam cylinder 16 by a connecting guideway 17, on the other end portion the said cylinder 15 is connected by a large radius elbow 19 to the water column tube 3.

The water column tube 3 is an extra strong tubular pipe made up of pipes of the standard commercial length, each pipe being connected to each other by a standard pipe coupling 18. This tube 3 extends from the end of the large radius elbow 19 to the joint connection 20 at the lower end of the actuating cylinder 9 of the tube 4, where it is fastened to same by a pipe elbow 20, which has threaded connection with said cylinder 9.

The actuating cylinder 9 which is part of tube 4 is a tubular cylinder enclosed at one end portion, just above this said end portion I have provided a threaded hole in the walls of the cylinder 9 for the pipe elbow 20 of the tube 3. The other or upper end portion contains a check valve body or chamber 13, which is cast as part of the actuating cylinder 9, said chamber 13 provides a casing to hold the fluid pumped from the oil well, and means for connecting the other portion of the tube 4 to the actuating cylinder 9. By referring to Fig. 3 of the illustration it will be seen that I have provided several ball valves 6 in the valve chamber 13. I do this to reduce the diameter of the valve chamber 13 to a minimum around the actuating passageway 10, this arrangement enables me to allow for the limited space in an oil well and also permits a homogeneous flow of fluid on all sides of the actuating passageway 10, or outlet adapted to increase the velocity of the fluid moving under pressure from the actuating cylinder 9. The ball valves 6 are kept in place, in the valve chamber 13, over their respective valve seats 21 by ribs 22 and are limited in their lift by a rod 23 that extends over them and through

the ribs 22.

Below the valve seats 21 I have provided a strainer 24 containing enough perforations 25 to protect the valve seats 21 and allow ample area for the valve system. On the upper end portion of the valve chamber 13 I have provided an outward threaded disposed cylinder 26 to permit of a typical union joint 27 for the connecting couple 28 that fastens the actuating cylinder 9 and the delivery cylinder 11 of the tube 4 together, also this outward disposed cylinder 26 supports and keeps in its place a delivery actuating passageway 12.

The delivery actuating passageway 12 is a tubular cylinder constructed to be supported in the actuating cylinder 9 and to be removable to allow for the placing of the ball valves 6 in their respective positions at the assembly of the tube 4 unit. It is adapted to cooperate with the actuating passageway 10 in guiding the flow of fluid from the actuating cylinder 9 into the delivery cylinder 11 when the velocity of said fluid is raising the pumped fluid out of the valve chamber 13.

The delivery cylinder 11 is a tubular cylinder extending from the surface of the earth to the valve chamber 13 which is located in the body of oil in the oil well 1. At the upper end portion I have provided a large radius elbow 29 to discharge the fluid horizontally from the tube 4 and at the lower end portion I have provided a lug to co-operate with the union joint 27 to fasten to the actuating cylinder 9 thus completing the entire unit termed tube 4. This delivery cylinder 11 can be made up of standard length commercial extra strong pipes each section of pipe being connected to each other by the usual standard pipe couplings if so desired.

The U tube pump will be supported by a base 30, upon a concrete pier 31. After the complete U tube pump is assembled and is lowered into the body of oil in the oil well 45 until the valve chamber 13 is an ample distance below the level 2 of the said oil I connect the pressure pump 8 to tube 3 and fill tube 4 with oil, tube 3 is then primed with water through valve 32, that is connected to a common water line, until the fluids in both tubes 3 and 4 balance each other, the pressure pump 8 is then operated and the pumping system will function.

Having thus described my invention, what I claim and desire to secure by Letters Patent is;

1. In an oil pump adapted to raise oil from oil deposits in the earth, a conduit adapted to hold a column of oil from said oil deposits, a conduit holding a column of water, said column of oil floating on and balanced by the pressure of the column of water, and a chamber having connection with the deposit, a passageway leading from said chamber, a discharge nozzle in said chamber

directed into said passageway to induce an injector action and forming a part of the oil column, and means for imparting reciprocating movement to the columns of oil and water; whereby oil is raised from the said oil deposits.

2. In an oil pump adapted to raise oil from oil deposits in the earth, a conduit adapted to hold a column of oil, a conduit holding a column of water, means to move said column of water in one direction by energy derived from some external source and permit its movement in a reverse direction by the weight of the column of oil and thus cause reciprocating movement of said columns, a suction nozzle in the oil column, a discharge passageway into which the nozzle is directed to induce an ejector action, and an inlet connection from the deposit to said passageway whereby oil is raised from the said oil deposits by said reciprocating movement of the columns of oil and water.

3. In an oil pump adapted to raise oil from oil deposits in the earth, two conduits extending from the surface of the earth adapted to hold two columns of fluid extending from the surface of the earth to the deposit, one a column of oil and the other a column of water, and ejector means including a nozzle for raising oil from oil deposits in the earth by a reciprocating movement of the two columns of fluid.

4. In an oil pump adapted to raise oil from oil deposits in the earth, two tubular cylinders extending from the surface of the ground to the oil deposit in the earth and joined together in said oil deposit, one of said cylinders adapted to hold a column of oil, a column of water in the other tubular cylinder, both columns of fluid having equal pressure and extending from the surface of the earth to the deposit, an inlet connection from the deposit to said oil column, a check valve in said connection, means for moving the column of water, whereby the check valve is opened by said movement, and closed by the weight of the column of oil, and ejector means including a nozzle operated by movement of said water column to raise oil from the deposit.

5. In an oil well pump for raising oil from deposits in the earth, connected conduits adapted to form a column of oil and a column of water extending from the surface of the earth to the deposit, means for giving a reciprocating movement to said columns, and ejector means including a nozzle operated by said movements of the columns to raise oil from the deposit.

6. In an oil well pump for raising oil from deposits in the earth, conduits adapted to form two connected columns of fluid, one of said columns of fluid having a lower specific gravity than the other and floating on and balanced by the column of greater spe-

- 4 cific gravity, there being a contracted passage in one of said conduits, a nozzle for forcing the fluid through said contracted passage, means for forcing the fluid of the 5 columns through said nozzle and a connection from the deposit to said contracted passage and cooperating with said flow to raise oil from the deposit.
7. In an oil well pump for raising oil from 10 deposits in the earth, a conduit adapted to hold a column of fluid from the deposit, a conduit connected with the first conduit and carrying a column of liquid of greater specific gravity than the said column of fluid, 15 said column of fluid from the deposit floating on and balanced by the column of liquid of greater specific gravity, a pumping means for imparting movement to the columns of fluid and liquid, an actuating passageway 20 in said first conduit, a nozzle in said conduit directed to discharge into said passageway, and an inlet connection from the deposit to said passageway cooperating with said movement to raise oil from the deposit.
- 25 8. In an oil well pump for raising oil from deposits in the earth, two tubular members extending from the surface of the earth to the deposit and joined together, each member being adapted to hold a column of fluid 30 extending from the surface of the earth to the deposit, one of said members having an open ended passageway, the other member carrying a column of liquid, a nozzle arranged to discharge liquid from the latter 35 member into said open end, a connection from the open end of said passage to the deposit, a check valve in said connection and means for imparting a reciprocating movement to the fluid in said members whereby 40 the check valve is opened by said movement in one direction and closed by movement of the column of fluid in a reverse direction.
9. In an oil well pump for raising oil from deposits in the earth, a body in the 45 deposit having a cross wall forming upper and lower chambers, a delivery passage way leading from the upper chamber, an actuating cylinder extending through said wall and having a discharge passage directed 50 toward said delivery passage, the walls of said body having openings leading to the lower chamber and the cross wall having passages therethrough, check valves controlling said passages, a discharge conduit 55 leading from the discharge passage to the surface of the earth, a conduit leading from the surface of the earth to said actuating cylinder and carrying a column of fluid, and means for causing reciprocating move- 60 ment of the fluid in said conduit to raise oil from the deposit.
10. In an oil well pump for raising oil from deposits in the earth, a body in the deposit having a cross wall forming upper and lower chambers, a delivery passage way 65 leading from the upper chamber, an actuating cylinder extending through said wall and having a contracted discharge passage directed toward said delivery passage, said cross wall being provided with openings 70 therethrough, upwardly extending walls between adjacent openings, ball check valves for controlling the openings, means for retaining the balls between said walls, the walls of the body having openings leading 75 from the lower chamber to the deposit, conduits extending from the surface of the earth and connected to the discharge passage and the actuating cylinder, a column of fluid in said latter conduit, and means for causing 80 movement of the fluid in said conduit to raise oil from the deposit.
11. In an oil well pump for raising oil from deposits in the earth, two tubular conduits leading from the surface of the earth 85 to the deposit and connected to form a U-tube construction, said conduits being adapted to hold a liquid forming a continuous U-shaped column of liquid leading from the surface of the earth, means connected with one of the conduits to impart a reciprocating movement to said column of liquid, a connection from the other conduit to the deposit, and ejector means including a nozzle in said conduit cooperating with said movement of the column to raise oil from the deposit. 90
12. In an oil well pump for raising oil from deposits in the earth, two tubular conduits leading from the surface of the earth to the deposit and connected to form a U-tube construction, said conduits being adapted to hold a liquid forming a continuous U-shaped column of liquid leading from the surface of the earth, a column of liquid in 100 one of said conduits, means connected with said conduit to impart a reciprocating movement to said column of liquid, an actuating passageway in the other conduit, a nozzle in said conduit arranged to discharge into said passageway, an inlet connection from the deposit to said passageway to cooperate with said nozzle to raise oil from the deposit, and a check valve in said inlet connection. 105
- 110 In testimony thereof I have hereunto subscribed my name.

WILLIAM FREDERICK McMAHON.
